Primary Examiner — Cathron Brooks*Assistant Examiner* — Melanie Pellegrini*(74) Attorney, Agent, or Firm* — Raymond Sun(57) **CLAIM**

The ornamental design for a ring-like input device, as shown and described.

DESCRIPTION

FIG. 1 is a perspective view of a ring-like input device showing my new design.

FIG. 2 is a front elevational view of the ring-like input device of FIG. 1.

FIG. 3 is a rear elevational view of the ring-like input device of FIG. 1.

FIG. 4 is a left elevational view of the ring-like input device of FIG. 1.

FIG. 5 is a right elevational view of the ring-like input device of FIG. 1.

FIG. 6 is a top plan view of the ring-like input device of FIG. 1; and,

FIG. 7 is a bottom plan view thereof.

The broken lines shown in the drawings illustrate portions of the ring-like input device and form no part of the claimed design.
